LINK CHAIN

Ernest Arthur Dennison, Longparish, Andover,
EnglandApplication April 22, 1939, Serial No. 269,535
In Great Britain April 11, 1938

5 Claims. (Cl. 59—35)

This invention relates to chains of the jointed link type and more particularly to endless chain-tracks for vehicles such as tractors and armoured cars or "tanks".

5 In a known method of chain-track construction, the chain comprises members arranged alternately along the length of the track, with their adjacent edges notched to allow engagement as hinges upon pins extending transversely of the track. These members will hereinafter be designated "sole plates" and "connecting pieces" respectively, in accordance with a recognized nomenclature. The connecting pieces are usually provided with spaced teeth or like means to engage the driving sprockets.

The present invention has for its main object to provide an improved mode of construction enabling the link-chain member or sole plate to be fabricated from more suitable materials than hitherto, thereby avoiding or reducing the risk of breakage and thus allowing the vehicles to operate at higher speed.

Another object of the invention is to build up the sole plate of a chain-track by preparing a ridged body or base piece of a length corresponding to the width of the track, slotting out the ridge at intervals in its length, and inserting in these slots or notches a plurality of stamped plates or the like having pairs of holes in register to receive the joint pins, the parts of the sole plate being then secured together by welding, brazing or the like. The stamped plates constitute links to transmit the pull in the endless track, and they can accordingly be made of high tensile or other suitable steel. The bodies or base pieces may be made from mild steel or other tubes, so that the material can be heat-treated or case-hardened after the construction of the complete sole plate.

40 The invention is hereafter more fully described in connection with the sole plates of chain tracks for vehicles, and with reference to the accompanying drawing, in which—

Fig. 1 represents a steel tube in the first stage 45 of manufacturing the improved sole plate.

Fig. 2 shows a pair of such tubes assembled together, and Fig. 3 shows a further stage of the manufacture.

Fig. 4 shows the assembled tubes reduced to 50 the ridged body or base piece for the sole-plate; Fig. 5 shows this body slotted transversely of the ridge.

Fig. 6 shows two of the several stamped plates employed in making up the sole plate.

55 Fig. 7 shows the finished sole-plate; Fig. 8

shows the sole plate hinged on one side to an adjacent connecting piece, and ready for hinged engagement with a corresponding connecting piece on the other side.

Figs. 9 and 10 illustrate two modifications 5 hereafter described.

In the preferred method of construction illustrated, each sole-plate is formed by welding together a pair of steel tubes such as *a*, Fig. 1, having flat surfaces *b* machined along the areas 10 which are to be in contact; after assembly, as illustrated in Fig. 2, with the two tubes welded together at *c* and along the faces *b*, the double tubular block is machined to produce another flat surface *e* extending along its length, transversely and also perpendicularly to the welded faces *b*, the metal being removed until the thickness at the top of the tubes is reduced almost to nil, as shown in Fig. 3. The block is then split longitudinally along the lower sides of the tubes 20 at the points *f*, by means of a pair of slitting saws *g*, so that the outer side portions *h* of the tubes can be removed by tearing away the thin connecting films at the top of the block; alternatively, the longitudinal slitting at the points *f* 25 may be performed before machining the flat surface *e*, and the latter operation carried down to a level which breaks through the interior surfaces of the tubes, so that the outer side portions *h* will fall clear as the top cut is finished. In 30 either case, there is left a body or base-piece *i* (Fig. 4), of which the cross section is approximately the shape of the inverted letter T, but with part-circular concave side faces *j*, representing the interior of the original tubes *a*. The 35 ridge *k* of this base-piece, representing the flat topped stem of the inverted T-shape, is then machined out by cutting a plurality of transverse notches or slots *l* at intervals in its length, for example six slots as shown in Fig. 5, for a 40 depth equivalent to about three-quarters of the bore of the original tubes, the spacing of these slots *l* corresponding to the notches in the sides of the connecting pieces with which the sole plate is to be associated.

45 A corresponding number of links *m* (Fig. 6), which may be stampings of high tensile steel, are also prepared to fit the slots *l* in the ridged body or base-piece, these links being of thickness equivalent to the width of the slots *l*, and 50 shaped like oval links with two holes *n* to receive the hinge pins of the track, but having their lower edges notched at *o* to fit over the remaining portion of the ridge *k* on the base-piece. The centers of the holes *n* in the links *m* are 55

spaced apart at substantially the same distance as the axes of the tubes *a* forming the body. The opposite ends of the links may be machined concentric with these holes *n*, parts *p* of the semi-circular ends being machined to a radius somewhat less than that of the tubes, so that these ends become tangential to the upper edges *r* of the links, which are substantially flush with the surface *e*; the parts *s* destined to seat in the bottom of the concave faces *j*, representing the bores of the original tubes are left of appropriate radius for this purpose, as shown in Figs. 6 and 7.

For assembling the parts of the composite sole plate, the stamped or other links *m* to be inserted in the cross slots *l* of the body ridge *k* may be threaded loosely upon the rods *t* (Fig. 6) of the same diameter as the hinge-pins *u* (Fig. 8), and then pressed into place in their respective slots, the rods *t* holding the links in alignment. The parts can then be welded together at the tops of the links or stampings *m* and at their opposite edges, and also along the seatings where the links rest on the concave surfaces *j*, the latter welds being particularly important and accessible in the case of the links at the ends of the sole plate.

Fig. 8 shows the sole plate partly connected in an endless track, and it will be noted that the pull exerted by the hinge pins *u* upon the sole plate will be supported by the solid metal of the links *m* fitted into the slotted ridge *k*, and that the body forms a stiff support or carrier for these links, ensuring their rigidity so that the hinges operate freely.

Instead of preparing the body or base-piece from two parallel tubes *a* fitted side by side as above described, like the barrels in a double-barrelled gun, there may be substituted the halves of a divided tube as illustrated in Fig. 9; the tube *a* is here provided with two parallel flat surfaces *b* on opposite sides and is then slit longitudinally at two points in asymmetrical relation to the flat faces, after which the two halves are placed back to back, welded together as described with reference to Fig. 2, and machined to produce the flat surface *e* at the top of the ridge. Again, the body or base-piece may be prepared from a single tube *a*, provided with two flat surfaces *b* intersecting at about 120 degrees, the tube being then split at a point in its circumference diametrically opposite to the intersection of the flat faces and opened out to bring the two halves back to back, the welding, machining and subsequent operations being substantially as above described.

What I claim is:

1. In the manufacture of link chains, the method of fabricating a link-chain member by the steps of securing a pair of metal tubes side by side, removing corresponding portions of both tubes to produce a curvilinear T-shaped cross-section, slotting said tubes transversely at intervals along the stem-portion of said T-shaped cross-section, inserting a plurality of link plates in said slotted stem-portion, and securing said link plates in registering positions. 10

2. In the manufacture of link chains, the method of fabricating a link-chain member by the steps of securing a pair of metal tubes side by side, removing opposite and corresponding portions of both tubes to produce a body of curvilinear T-shaped cross-section, slotting said body transversely of the axes of said tubes and at intervals along said body, and securing a plurality of link-joint plates edgewise in the slots of said body. 20

3. In the manufacture of link chains, the method of fabricating a link-chain member by preparing from metal tube material a ridged body with concave side faces of a length substantially equal to the width of the chain, slotting out said body at intervals along and transversely of the ridge, and securing in the slotted ridge and concave side faces a plurality of link-joint plates. 25

4. In the manufacture of link chains, the method of fabricating a link-chain member by splitting a metal tube longitudinally, opening out said tube so as to bring the two halves back to back, shaping the opened-out tube to produce a curvilinear T-shaped cross-section, slotting said tube at intervals along the stem-portion of the T-shaped cross-section, and securing in said tube a plurality of link-joint plates, each of said plates extending transversely of the length of said tube. 30 35

5. In the manufacture of link chains, the method of fabricating a link-chain member by the steps of assembling a pair of steel tubes side by side, each of said tubes having a flat on its outer surface and the two flats being in contact, welding said assembled tubes together, slitting said tubes longitudinally to remove portions remote from said contacting flats, milling said tubes longitudinally to produce a flat surface perpendicular to said contacting flats, slotting said tubes transversely through but for less than the entire width of said contacting flats, and securing in the transverse slots of said tubes a plurality of steel plates with registering holes for engaging the joint-pins of the chain. 40 45 50 55

ERNEST ARTHUR DENNISON.
